UNITED STATES PATENT OFFICE.

WILLIAM A. KELSEY, OF MERIDEN, CONNECTICUT.

DESIGN FOR A CARD.

SPECIFICATION forming part of Design No. 18,025, dated January 24, 1888.

Application filed November 18, 1887. Serial No. 255,559. Term of patent 7 years.

To all whom it may concern:

Be it known that I, WILLIAM A. KELSEY, of Meriden, in the county of New Haven and State of Connecticut, have invented and produced a new and original Design for Cards, of which the following is a specification, reference being had to the accompanying drawings, forming a part thereof, in which—

Figure 1 is a plan view of a card embodying my design, and Fig. 2 is a longitudinal sectional view on line $x x$ of Fig. 1.

The object of my invention is to produce a neat and attractive card having a raised ornamental border.

The leading feature of my design consists in a card having plain flat body and a raised

border or margin of a rope or cable like configuration.

A represents a plain flat card, and B is the raised cable-like border or margin thereof. 20

What I claim is—

The design for a card herein shown and described, consisting in a card having a plain flat oblong body, A, rounded at its ends, and a raised border of cable or rope like configuration around the edge or margin thereof, as set forth. 25

WILLIAM A. KELSEY.
